FLEXIBLE FABRIC SUPPORT FOR SLING CHAIRS

Dorothy W. Schindele, Los Angeles, Calif.

Application January 8, 1954, Serial No. 28,421

Term of patent 3½ years

(Cl. D15—1)

Fig. 3.

Fig. 2.

Fig. 4.

Fig. 1 is a front elevation of a flexible fabric support for sling chairs embodying my new design;

Fig. 2 is a side elevation of the support;

Fig. 3 is a rear elevation thereof; and

Fig. 4 is an enlarged fragmentary view illustrating the detail of the triangular inserts.

I claim:

The ornamental design for a flexible fabric support for sling chairs, as shown and described.
